UNITED STATES PATENT OFFICE

MOSES JACOBSON, OF NEW YORK, N. Y., ASSIGNOR OF ONE-HALF TO ADOLPH HERZFIELD, OF BROOKLYN, NEW YORK

MULTIPLE CONDENSER

Application filed March 30, 1925. Serial No. 19,467.

My invention relates to improvements in condensers for controlling multiple stages of radio frequency or other circuits by a single tuning device, also for use as an efficient low loss vernier condenser of variable capacity.

One of the objects of my improvement is— to replace three or more condensers by one condenser in tuned radio frequency receivers 10 or neutrodynes and the like.

Another object of my improvement is to produce an improved condenser, which facilitates the separation of low wave lengths, or one which has characteristics approaching 15 those of a straight line frequency condenser.

Other objects and advantages will herein-after appear.

I attain these objects by the multiple condenser, one form of which is illustrated in 20 Figs. 1 and 2 and another and preferred form is shown in Figs. 3 and 4 of the accompanying drawings or by any equivalent or obvious modification of the same.

In the drawings, Fig. 1 is a part section on 25 the line 1—1 of Fig. 2 of one form of my condenser, showing sundry parts in elevation and showing one of the posts, which are hereinafter described, as partly broken away, to better expose to view the central gear, 30 which is hereinafter described.

Fig. 2 is a section on the line 2—2 of Fig. 1; Fig. 3 is a plan of another and preferred 35 form of my condenser, showing the radio cabinet as broken away at the sides thereof.

Fig. 4 is a vertical section on the line 4—4 of Fig. 3.

Fig. 5 is a detail of a preferred form of 40 rotor plates, which may be used in either or both of the above described forms of my multiple condenser or in any other condenser.

Similar numerals refer to similar parts throughout the several views:

11 designates the front panel of a radio 45 cabinet, to which may be connected the metal front plate 12 of my multiple condenser by any suitable means, such as the Z-bars 40, which are shown in Fig. 1 of the drawings as secured by screws to said plate 12 and 50 panel 11.

A metal rear plate 13 is connected to said plate 12 by means of metal posts or spacing rods 14.

A controller shaft 15 and rotor spindles 16, 17 and 18 are pivotally mounted in horizontal positions in said plates 12 and 13; the shaft 15 passes through a pair of stator plates 29, hereinafter described, and extends forwardly through said panel 11, and it has secured thereto the knob 19 and pointer 55 or index 20.

A dial 21 may be connected to said panel 11 in any suitable manner, and suitable insignia placed on said dial.

Motion is transmitted from said controller shaft 15 to said spindles 16, 17 and 18 by means of a central spur gear 22 and the driven spur gears 23, 24 and 25, which are mounted on said shaft 15 and spindles 16, 17 and 18 respectively, as shown in Fig. 70 2, where said gears are represented by their pitch circles.

The pitch diameter of said gear 22 is preferably half as large as the pitch diameters of said gears 23, 24 and 25, thereby 75 causing the pointer 20 to rotate through 360 degrees for the 180 degrees of rotation of the spindles 16, 17 and 18 from the position of minimum capacity to that of maximum capacity of sets of rotor plates 26, 27 and 28, which are secured to said spindles 16, 17 and 18, and which are shown in Fig. 1 as positioned intermediate of a set of stator plates 29, which are shown in Fig. 2 80 as triangular in shape and held in position by means of said posts 14.

Suitable spacing rings or ferrules may be employed for spacing said rotor plates and stator plates apart from each other, if desired; said plates may also be soldered to said spindles and posts respectively.

The rotor plates 26, 27 and 28 may have each the approximate shape of a segment of a circle, as shown in Figs. 1, 3 and 5, 95 and the sets of said rotor plates serve as component condensers with one common set of stator plates between them, forming therewith one multiple condenser with one controller shaft 15 to be turned by one 100

knob 19 thereon and to carry a pointer 20 to rotate in front of a dial 21.

To insulate said stator set from said rotor sets the gear 22 may be made of hard rubber, formica or any other highly insulating material, and the spindles 16, 17 and 18 may also be journalled in bushings 39 of hard rubber, secured to said plates 12 and 13.

10 Electrical connection may be made to said rotor sets by means of spring plates 30, which are in contact with the rear ends of said spindles 16, 17 and 18, and which are insulated from said plate 13 by means of 15 bakelite blocks 31, which carry binding posts made up of screws 32 and taps 33, which are in contact with said springs 30.

The springs 30 are shown in Fig. 1 as somewhat displaced towards the center of 20 the plate 13, to illustrate the flanges 34, which are provided on said springs 30, to prevent rotation of the latter on said blocks 31 when screwing home said caps 33 with a suitable wire and a washer 35 therebetween 25 and said spring 30.

The stator sets of my multiple condenser may be electrically connected to the radio circuit by means of a metal binding post 36—37—38 connected to the rear plate 13.

30 In the form of my multiple condenser shown in Figs. 3 and 4 the gear 22 is replaced by a pair of right handed worms 52 and a left handed worm 52^a secured to a controller shaft 45, which is supported by the 35 front panel 11 and a vertical plate 41, in a plane parallel to sets of rotor plates 56, 57 and 58 on vertical spindles 46, 47 and 48, said rotor plates to rotate intermediate of a common set of stator plates 59, secured 40 to vertical posts 44, which are connected at their ends to a pair of horizontally positioned end plates 42, to which said spindles 56, 57 and 58 are pivotally connected.

The sides of the stator plates 59 are convex outwardly as shown.

Said worms 52 are in mesh with worm gears 53 and 54 situated on one side of the controller shaft 45, and said worm 52^a is in mesh with the worm gear 55, situated on the 50 other side of said shaft 45, thereby causing said worm gears to be rotated all in the same direction when said shaft 45 is turned.

A thrust ring 69 is shown in Fig. 3 as secured to the shaft 45 near the rear end 55 thereof by means of a set screw 70.

The front part of said shaft 45 passes through a sleeve 43, which is journalled at its ends in said panel 11 and a bracket 60, and has secured thereto the pointer 50 to 60 rotate in a plane parallel to another pointer 49, which is secured to the end of said shaft 45 in front of the dial 21.

Motion may be transmitted from the controller shaft 45 to the sleeve 43 by means 65 of a pair of bevel gears 64 and 65, which

are shown by their pitch cones in Figs. 3 and 4, and which are secured respectively to said spindle 47 above said worm gear 54 and to a counter shaft 61, which is journalled at its ends in said panel 11 and said bracket 70 60, and has secured thereto the spur gear 62 in mesh with a similar spur gear 63 secured to said sleeve 43; both spur gears 62 and 63 are represented by their pitch circles in Fig. 4.

The index 50 may be geared in this way to have the same angular velocity as the rotor spindles 46, 47 and 48, while the index 49 may have the velocity of the controller shaft 45; the distance on the dial 21 passed by said pointers 50 and 49 is, of course, proportional to their velocities. The pointer 49 will, therefore, indicate on a larger scale on said dial 21 the position of said rotor sets with relation to said stator plates.

85 A pair of screws 51 may be employed to connect said bracket 60 to the rear of the panel 11, which may be situated further forward than as shown in Fig. 3 to allow the gear 65 to be placed in front of the gear 54, 90 when said bracket 60 may be straight instead of being offset horizontally, as shown in Fig. 4.

A preferred form of a rotor plate 66 is shown in Fig. 5, in which plate I provide 95 a large number of small apertures 67 in addition to the opening 68 for a rotor spindle, the number of said apertures 67 gradually increasing from one end of said plate 66 to the other end, thereby obtaining 100 a straight line wave length or straight line frequency characteristic or any other desired rate of variation of capacity in this or any other condenser.

The stator plates may also be provided 105 with apertures, if desired.

Many changes may be made in the details of my multiple condenser without departing from the main scope of my invention, and parts of my invention may be used without 110 other parts; I do not, therefore, restrict myself to the details as shown in the drawings; but I intend to include also all equivalents and obvious modifications of the same within the scope of my invention.

115 I claim as my invention, and desire to secure by Letters Patent:

1. In a multiple condenser for tuning multiple circuits multiple sets of rotor plates, a separate electrical lead from each 120 of said sets, for connection in said circuits, a set of stator plates common to said sets of rotor plates, a controller shaft, a fixed mechanical coupling therebetween and said rotor sets, said shaft to be rotated at a 125 higher angular velocity than said rotor sets, a stationary dial, a pointer, secured to said shaft, for accurately indicating on said dial the position of said rotor plates with relation to said stator plates, and another point- 130

er, operatively connected to one of the rotor sets, to indicate on a small scale the angular displacement of said rotor sets.

2. In a multiple condenser for tuning multiple circuits multiple sets of rotor plates, said sets being insulated from each other and having each a separate electrical lead for connection in said circuits, a set of stator plates common to said sets of rotor plates, a controller shaft in a plane parallel to said plates, worm gears connected to said rotor sets and situated on opposite sides of said shaft, one or more right-handed worms on said shaft, to actuate the worm gears situated on one side of said shaft, and one or more left-handed worms to actuate the worm gears situated on the other side of said shaft, thereby causing said gears to be rotated all in the same direction by said shaft.

3. In a multiple condenser for tuning multiple circuits, multiple sets of rotor plates, a separate electrical lead from each of said sets for connection in said circuits, a set of stator plates common to said sets of rotor plates, a controller shaft, a fixed mechanical coupling therebetween and said rotor sets, said shaft to be rotated at a higher angular velocity than said rotor sets, a stationary dial, a pointer, secured to said shaft, for indicating on a larger scale on said dial the position of said rotor sets with relation to said stator plates and another pointer swivelled on said shaft coaxially with said first mentioned pointer and operatively connected to one of said rotor sets, to indicate on a small scale on said dial the position of said rotor sets.

Executed March 25, 1925.
MOSES JACOBSON.
